Primary Examiner — Marissa J. Cash

(74) Attorney, Agent, or Firm — Tucker Ellis LLP

(57) **CLAIM**

The ornamental design for a wheel chock as shown and described.

DESCRIPTION

FIG. 1 is a perspective view of a wheel chock showing our new design;

FIG. 2 is front view of the wheel chock illustrated in FIG. 1;

FIG. 3 is a rear view of the wheel chock illustrated in FIG. 1;

FIG. 4 is a left side view of the wheel chock illustrated in FIG. 1;

FIG. 5 is a right side view of the wheel chock illustrated in FIG. 1;

FIG. 6 is a top view of the wheel chock illustrated in FIG. 1; and,

FIG. 7 is a bottom view of the wheel chock illustrated in FIG. 1.

The broken lines show portions of the wheel chock that form no part of the claimed design.

1 Claim, 7 Drawing Sheets
